LOCK, LATCH, AND THE LIKE

Samuel Bartlett McKenzie, Toronto, Ontario,
CanadaApplication June 27, 1940, Serial No. 342,699
In Great Britain June 27, 1939

4 Claims. (Cl. 292—357)

This invention concerns improvements in locks, latches or the like (hereinafter all referred to as and included in the term latches) and has especial reference to operating mechanism for latches.

A general object of the invention is to provide an improved latch operating mechanism while a further and more particular object of the invention is to provide a self-restoring latch operating mechanism in which, after operation, the parts will return to their original positions. This is a very material point in the case of latch operating mechanism employing operating members or handles of lever form for these look very unsightly if they do not come back to their original, usually horizontal, positions.

A further object of the invention is to provide in a lock operating mechanism in combination with the self-restoring feature, means for retaining the roses or escutcheon plates (hereinafter referred to as roses), in their operative positions without the use of screws or equivalent fastening members, thereby avoiding liability of the hands or clothing of a user being scratched or torn by the usual fastening means and avoiding the latch operating mechanism becoming unsightly and rattling.

According to one aspect of this invention there is provided an operating mechanism for a door latch including a rotatable operating spindle and a non-rotatable reaction member, interengaging restoring portions provided respectively on the spindle or a part carried thereby and on, or in, the reaction member and adapted on partial rotation of the spindle to stress a spring, whereby on the spindle being released it is automatically restored to its initial position relative to the reaction member.

According to another aspect of the invention there is provided an operating mechanism for a door latch including a rotatable operating spindle, a non-rotatable reaction member, and means for restoring the spindle to its original position after partial rotation, such means comprising cam and follower members urged together by a spring, and one of such members being, on the partial rotation of the spindle, displaced against the action of the said spring.

The spring referred to above will usually be a metal wire spring of helical form but a rubber element or even blade springs may be used in some cases and it should be understood that the expression "spring" is intended to include these and like alternatives.

The arrangement is such that the said spring

causes the said restoring portions or the said cam and follower to be pressed continually into contact with one another and preferably acts in the direction of the axis of the operating spindle, such spring being stressed when the co-operating restoring portions or the cam and follower separate.

One of the restoring portions or the said cam is preferably formed in or carried by a rose through which the operating spindle passes, and the other and co-operating restoring portion or the follower is carried by the spindle either on a part fixed thereto, as, for example, on the boss of an operating lever or handle, or on a portion rotating with the spindle but slidable axially along the latter, and the said spring is preferably in the form of a helical compression spring urging the co-operating restoring portions or the cam and follower into contact with one another either by direct action on one of these parts or by action thereon through the medium of the operating spindle.

The said spring also serves to press the rose or roses of the operating mechanism into contact with the door upon which this mechanism is mounted, so retaining the rose or roses in position without the use of auxiliary screws or equivalent additional fastening means.

The latch operating mechanism may be arranged either to operate the latch solely by partial rotation of the operating spindle or by endwise movement of the operating spindle, or if desired by a combined rotary and endwise action of the spindle.

One of the co-operating restoring members at least is preferably in the form of a cam having one or more V-like cam surfaces, each V-like cam surface having two opposed helical surfaces while the other co-operating restoring portion is preferably of a very similar character but it could be in the form of a roller or pin or other suitable follower member.

Further features of the invention will become apparent from the subsequent illustrative description of certain embodiments of the invention given by way of example.

In the drawings:

Fig. 1 is a front elevation of a latch operating mechanism constructed in accordance with this invention.

Fig. 2 is a horizontal section on line II—II of Fig. 1.

Fig. 3 is a perspective view of a portion of the lever handle shown uppermost in Fig. 2.

Fig. 4 is a part sectional perspective view of the

rose co-operating with the lever handle of which a part is shown in Fig. 3.

Fig. 5 is a cross-sectional plan view similar to Fig. 2 but showing slightly modified constructions of roses.

Fig. 6 is a sectional plan view of a modified form of latch operating mechanism constructed in accordance with this invention but designed for use where the mechanism is operable from one end of the operating spindle only, and

Fig. 7 is a further horizontal sectional plan view showing a further modified construction of latch operating mechanism in accordance with this invention, and in which the operating spindle does not necessarily move endwise when the spindle is rotated.

Although in Figs. 1 to 6 the latch mechanism illustrated employs an operating member in the form of a lever it should be understood that it is not essential that the operating member should be a lever. It could for example be a knob as is shown in Fig. 7, but the self-aligning or self-restoring character of the latch operating mechanism is especially suitable for use with lever handles and therefore that form of operating member has been illustrated in Figs. 1 to 6 of the drawings.

Referring to Figs. 1 to 4 of the drawings it will be seen that the latch operating mechanism illustrated there comprises an operating spindle 1 of square cross-sectional form. This spindle is adapted to pass through a hole 2 perpendicular to the face of the door 3, and the spindle has fixed upon one end an operating member 4 having a lever 5 projecting laterally from the outer end of a long, more or less cylindrical or slightly conical boss 6.

At the other end of the spindle 1 is provided with an operating member 7 which has a lever 8 projecting radially from the outer end of a long boss 9, and this operating member is, in outward appearance, substantially identical with the operating member 4.

However, the operating member 7 is not permanently fixed upon the spindle 1 but is adjustable thereon, having a square axial recess 10 provided in its boss 9 into which the spindle 1 fits, the operating member 7 and the spindle being secured in adjusted interfitting relation by means of a cross pin 11 passing through any selected one of a series of spaced transverse holes 12 provided in the spindle 1 and through a pair of diametrically opposite bores 13 provided in the boss 9 of the operating member 7. The pin 11 is very slightly less in length than the diameter of the boss 9 at the position at which the pin 11 passes therethrough and the ends of the pin 11 are rounded off. The pin 11 having once been inserted in the boss 9 and spindle 1 is retained in this position by the surrounding rose to be frequently described.

A pair of roses are provided one for each side of the door 3. These roses are marked in the drawings respectively by general references 14 and 15. The rose 14 has a central cylindrical tubular body 16 provided at its inner end with an inwardly directed transverse flange 17 provided with a central hole 18 through which the spindle 1 freely and rotatably passes, and at the outer end the body 16 of the rose is provided with an annular face plate 19 of any convenient and suitable design which is free of screw holes.

The rear surface 20 of the face plate 19 is preferably of slightly conical form so that the face plate bears upon the door only at the outer mar-

gin thereof, and at the back the face plate 18 is provided with one or more, in the example shown with three, spikes 21 adapted to engage in the adjacent surface of the door 3 when the rose is in use so as to prevent the rose rotating about its axis.

The inner diameter of the tubular body 16 of the rose 14 is enlarged slightly in diameter at 22 as clearly shown in Fig. 2 so as to avoid the boss 6 of the operating member 4 becoming scratched by the rose due to the reciprocation of the boss relative to the rose as will subsequently be described.

On the inner side of the annular flange 17 of the body 16 of the rose 14 is mounted a hard metal washer 23 against which abuts one end of a helical compression spring 24 abutting at its other end against a similar hard metal washer 25 mounted in the bottom of a cylindrical recess 26 formed in the inner end of the boss 6 of the operating member 4 and which recess 26 is coaxial with the spindle 1. As will be seen the spring 24 is also coaxial with the spindle 1 and surrounds the latter and the natural tendency of the spring, which is inserted under load, is to tend to draw the spindle 1 out of the rose 14 and subsequently to pull the operating member 7 towards the door. At the same time the spring 24 presses the rose 14 towards the adjacent surface of the door.

The rose 15 is very similar in outward appearance and general construction to the rose 14, being provided with a plate 19', a tubular body 16', an enlarged bore 22', spikes 21' and a slightly conical rear surface 20'.

In this case, however, no compression spring is disposed within the rose and the construction of the inner end of the boss 9 of the operating member 7 is different to that of the boss 6 of the operating member 4. The inwardly directed flange 17' of the body 16' of the rose 15 carries on the surface nearest the operating member 7 a pair of diametrically opposed V-shaped cam pieces 27 (see Fig. 4) each having helical surfaces 28 meeting at one end at the apex 29 and terminating at the other end at diametrically opposed radial gaps 30 provided in the flange 17'.

It will be seen that each of the surfaces 28 is virtually a portion of an internal screw thread arranged within the body 16' of the rose and that these cam surfaces are arranged around the central axis of the operating spindle 1 and each surface 28 is oblique with respect to the axis of the spindle 1.

Instead of the cam pieces 27 being formed integrally with the body 16' and flange 17' of the rose 15 they can be formed on a separate member mounted upon the said flange 17' if desired.

The end of the boss 9 of the operating member 7 adjacent the cam pieces 27 of the rose 15 is provided with a pair of diametrically opposed V-shaped recesses generally indicated by the references 31 and 32, the recess 31 being formed of a pair of similar helical surfaces 33 meeting at a radial recess 34 in the operating member boss 9, and the other recess 32 being formed of a pair of helical surfaces 35 exactly similar to the surfaces 33 meeting one another at a radial recess 36 similar to the radial recess 34 above described and formed in the operating member boss 9. The adjacent helical surfaces 33 and 35 meet one another in peaks 36, 37.

It will be understood that the cam pieces 27 fit more or less exactly one into each of the recesses 31 and 32 of the boss 9 of the operating

member 7 and that when the operating levers 5 and 8 are in their normal horizontal (or other predetermined position) the peaks 36 and 37 of the boss 9 rest in the radial gaps 30 of the flange 17' of the body 18' of the rose 15 so firmly positioning the operating levers in the predetermined position from which position they cannot move without the application of some manual pressure.

When mounting the latch operating mechanism upon a door, first of all the spring 24 is threaded upon the spindle 1, then the rose 14 is threaded upon the spindle, and the latter is passed through the hole 2 in the door 3 and the rose 14 engaged with the door, the rose 18 is then threaded upon the spindle at the opposite side of the door to the rose 14 and endwise pressure towards the rose 15 is exerted on the operating member 4 and spindle 1 so compressing the spring 24. Then the operating member 7 is mounted upon the spindle 1 and set thereon in the appropriate position after which the pin 11 is threaded through the bores 13 in the boss 9 of the operating member 7 and through the selected cross bore 12 of the spindle 1 so locking the spindle 1 and the operating member 7 together. It should be understood, of course, that the pin 11 is inserted into the bores 13 of the boss 9 and into the appropriate cross bore 12 of the spindle 1 while these bores are disposed outside the tubular body 16' of the rose 15 and while the spring 24 is still compressed, and it is not until the pin 11 is fully home that the axial pressure on the operating member 4 and spindle 1 is released, so permitting the spindle 1 to move axially under the action of the spring 24 in the direction of the arrow A (Fig. 2), so pulling the cam surface bearing end of the boss 9 of the operating member 7 into engagement with the cam pieces 27 of the rose 15 and the pin 11 within the rose into a position as shown in Fig. 2 where it cannot accidentally fall out.

It will be seen that not only does the spring 24 press the rose 14 on to the surface of the door but it also, through the action of the spindle 1 and the connection of the latter with the boss 9 of the operating member 7, pulls the rose 15 on to the opposite face of the door, and so both roses are urged into and held in contact with the opposite faces of the door automatically without the use of any securing screws.

The helical cam faces 28 and the co-operating faces 33 and 35 of the cam recesses 31 and 32 in the boss of the operating member 7 are of rather large pitch and it will be clearly understood that, assuming the parts are initially in the position shown in Figs. 1 and 2, on partially rotating the spindle 1 by means of either of the operating members 4 or 7 the peaks 36 and 37 of the boss 9 of the operating member 7 will leave the radial gaps 30 of the rose 15 and ride up the cam surfaces 28 of the cam pieces 27 irrespective of whether the operating member is turned in clockwise or anti-clockwise direction, and thus the spindle 1 will be caused to move axially in the direction of the arrow B (Fig. 2) so compressing the spring 24 which will, as soon as the operating member by which the spindle has been turned is released, cause, through the medium of the interengaging cam surfaces of the boss 9 and rose 15, the operating members to return to their initial positions and become temporarily locked in these positions through the interengagement of the peaks 36 in the radial gaps 30.

Thus in this construction the spindle 1 not

only makes a partial rotation but it moves axially and either the rotation or the axial movement of the spindle, or the combination of both movements, may be used to operate the latch mechanism whichever appears to be more appropriate for the particular latch mechanism.

It will be understood that the bosses 6 and 9 of the operating members 4 and 7 slide axially relative to the roses 14 and 15, respectively, over a short distance each time the operating spindle is turned and it is to avoid scratching the parts of the bosses 6 and 9 of the operating members 4 and 7 which slide in and out of the roses 14 and 15 that the bodies of these roses are provided with the enlarged bores 22 and 22' previously described.

In the modified construction of latch operating mechanism shown in Fig. 5 all the parts with the exception of the roses are the same as those described with reference to Figs. 1 to 4 and the only way in which this construction differs from that previously described lies in the fact that the tubular bodies 16 and 16' of the roses extend outwardly from the face plates 18 and 18' of the roses instead of inwardly, this arrangement being employed so as to avoid the necessity for drilling such a large hole as the hole 2 shown in Fig. 2 in the door, this hole in the construction shown in Fig. 5 being replaced by one of much smaller diameter and marked 2'.

In Fig. 6 a modified arrangement is described which is in all respects the same as that described with reference to Figs. 1 to 4 with one exception, namely, that the construction shown in Fig. 6 is intended for use on a cupboard door where a handle is not necessary on the inside of the door and therefore the operating member 7 of the arrangement described in Figs. 1 to 4 is replaced by a boss 38 constructed at its inner end, precisely like the inner end of the boss 9 of the operating member 7 and co-operating with the rose 15 exactly in the same way as the operating member 7.

In some cases it may be undesirable for the spindle 1 to have an axial sliding movement and in the modified arrangement shown in Fig. 7 means are provided to produce the same results as those obtained with the constructions described with reference to Figs. 1 to 6 but without the necessity of the axial movement of the operating spindle taking place.

In the embodiment of the invention illustrated in Fig. 7 the operating spindle 39 (corresponding to the previously described spindle 1) carries an operating knob 40 at one end and a similar operating knob 41 at the opposite end, the knob 40 being fixed to the spindle 39 and the operating knob 41 being adjustably mounted on the spindle by means of a pin 42 passing diametrically through a cylindrical boss 43 provided on the knob and through any selected one of a plurality of spaced transverse bores 44 provided in the operating spindle 39. The knob 40 has a central long cylindrical tubular boss 45 coaxial with the spindle 39 and rotatably mounted in the tubular body 46 of a rose 47, while the central boss 43 of the knob 41 rotatably fits into the tubular body 48 of the rose 48.

The tubular body 49 of the rose 48 has at its inner end an inwardly directed annular flange 50 against which the inner end of the boss 43 of the knob 41 is adapted to engage.

The roses 47 and 48 each have a peripheral flange 51, a somewhat conical inner surface 52, and a plurality of spikes 53 and these roses func-

tion and are retained in position on the door in substantially the same manner as that described with reference to the other constructions of the invention illustrated in Figs. 1 to 6.

The tubular body 46 of the rose 47 is also provided at its inner end with an inwardly directed annular flange which is marked 54 and this flange carries on its outer side, that is the side nearest the knob 40, a pair of V-shaped cam pieces 55, 56 corresponding in function to the cam pieces provided in the rose 15 described with reference to Figs. 1 to 4.

Between the cam pieces 55, 56 and the knob 40 and within the tubular boss 45 of the latter a cam or follower sleeve 57 is arranged and this sleeve has a square axial hole through which the square spindle 39 passes freely, the arrangement being that the sleeve rotates with but is axially slidably upon the spindle 39. A helical compression spring 58 housed within the tubular boss 45 of the knob 40 and surrounding the spindle 39 engages at one end against the outer end of the slidable cam sleeve 57 and at the opposite end against the inner surface of the knob 40 and this spring is under compression so that it always urges the cam sleeve 57 in a direction along the spindle 39 towards the knob 41.

The cam sleeve 57 is, at the end remote from the knob 40, provided with a pair of diametrically opposite V-shaped recesses 59 in which respectively engage the V-shaped cam pieces 55 and 56 of the rose 47. The cam surfaces of the cam pieces 55 and 56 and the cam surfaces 39 of the cam sleeve 57 are preferably each formed by a part of a helix of large pitch and correspond substantially to the cam surfaces described with reference to Figs. 3 and 4 of the drawings in particular, and the functions of these co-operating cam surfaces are the same as those just referred to.

It will be clearly understood from an inspection of the drawings and from the foregoing description that, when the operating spindle 39 is partially rotated, the cam surfaces 59 of the cam sleeve or follower 57 will ride up the cam surfaces of the cam pieces 55 and 56 of the stationary reaction member or rose 47 and the cam sleeve will therefore be caused to slide along the spindle 39 towards the knob 40 and will so compress the spring 58 whereby, on the knob which has been held to turn the spindle being released, the spring 58 will tend to expand and through the co-operation of the cam surfaces referred to cause the spindle 39 to return to its original position in which it will be generally held in the same way as the spindle 1 is positioned in its original position and as previously described.

It will be understood that in the arrangement shown in Fig. 7 the roses 47 and 48 are retained against the surfaces of the door by the action of the spring 58 just as the roses 14 and 15 are retained against the door by the spring 24 previously described.

In Fig. 7 the inner end of the tubular boss 45 of the knob 47 is shown to be spaced somewhat from the inwardly directed annular flange 54 of the body 46 of the rose. This clearance is left so that the spindle can be moved axially by pushing on the knob 40 or by pulling on the knob 41 if desired for the purpose of operating a latch, but if only the rotation of the spindle 39 is to be used for operating the latch then the tubular boss 45 may beat upon the flange 54 so as to prevent any axial movement of the spindle at

all and in that case the method of attaching the knob 41 would have to be by means of a grub screw or by some other means other than that shown. However, the strength of the spring 58 may, if desired, be such that even with the clearance shown in Fig. 7 between the tubular boss 45 and the rose flange 54, the spindle cannot be moved endwise without exerting considerably more force than would usually be exerted upon the spindle 39 and the knob 40.

It will clearly be seen that in each embodiment of the invention described the cam surfaces and the spring cooperating therewith are completely housed within the roses and operating members and the complete door furniture is of a neat external appearance.

Whereas I have described my invention by reference to specific forms thereof, it will be understood that many changes and modifications may be made without departing from the spirit of the invention.

I claim:

1. An operating mechanism for a door latch comprising spaced roses arranged in axial alignment with each other, a hollow boss arranged in each rose and rotatably and slidably mounted each in its own rose, a non-cylindrical spindle having its ends secured in the said bosses, a spring mounted in one of said bosses and urging said boss outwardly away from its associated rose, a cam formed on the inner end of said other boss, a cooperating cam surface formed on the rose in which said last named boss is mounted, whereby when either boss is rotated a simultaneous longitudinal movement of the bosses in their respective roses takes place, and when rotative movement has ceased, the bosses are returned to their original initial position.

2. An operating mechanism for a door latch comprising, two roses spaced apart and arranged in axial alignment with each other, a non-cylindrical shaft, a hollow boss provided with an operating handle mounted on one end thereof, said hollow boss rotatably and slidably mounted in one of the roses, a second hollow boss provided with an operating handle mounted on the other end of the non-cylindrical member and yieldably and slidably mounted in the other said rose, cooperating cam surfaces mounted on the last said boss and on the rose in which it is rotatably and slidably mounted, a spring member housed in the first said rose and its associated boss, said spring member yieldingly holding the cooperating members in engagement with each other.

3. An operating mechanism for a door latch comprising, two roses spaced apart and arranged in axial alignment with each other, a non-cylindrical shaft, a hollow boss provided with an operating handle mounted on one end thereof and said hollow boss rotatably and slidably mounted in one of the roses, a second hollow boss provided with an operating handle mounted on the other end of the non-cylindrical member and yieldably and slidably mounted in the other said rose, cooperating cam surfaces mounted on the last said boss and on the rose in which it is rotatably and slidably mounted, a spring member housed in the first said rose and its associated boss, said spring member yieldingly holding the cooperating members in engagement with each other, and whereby upon the rotation of either of the bosses there is imparted a simultaneous axial movement of the bosses and tensioning of said spring member, and upon release of the ro-

tating effect the tension of the spring returns the bosses to their initial position.

4. An operating mechanism for a door latch comprising, a rose secured to one side of a door and having a central hollow portion extending into a hole extending through the door, a boss having one end housed within the rose, a helical spring enclosed by said boss, said boss being capable of axial and rotary movement with respect to the rose, a non-cylindrical shaft having one end secured in the boss and extending through the hole in the door and outward beyond the limits of the other face of the door, a second rose secured to the opposite face of the door in axial alignment with the first said rose and having a central portion extending into the

5 hole in the door, a second boss having one end housed in said second rose and capable of axial and rotary movement with respect thereto, a cam surface formed on the inner end of said last named rose, said second boss secured to the other end of the non-cylindrical member, said second boss being provided with cam members which cooperate with the cam surfaces on the said last named rose and operate only on one of said bosses whereby the bosses may be rotated and have imparted thereto a longitudinal movement which tensions the said spring and upon release of the pressure on the operating mechanism the bosses are returned to their initial position by said spring.

SAMUEL BARTLETT MCKENZIE.
